UNITED STATES PATENT OFFICE

FRANK S. PIERCE, OF MINNEAPOLIS, KANSAS.

CARBURETER.

1,084,028.

Specification of Letters Patent. Patented Jan. 13, 1914.

Application filed April 22, 1912. Serial No. 692,413.

To all whom it may concern:

Be it known that I, FRANK S. PIERCE, a citizen of the United States, residing at Minneapolis, in the county of Ottawa and 5 State of Kansas, have invented certain new and useful Improvements in Carbureters; and I do declare the following to be a full, clear, and exact description of the invention, such as will enable others skilled in the art 10 to which it appertains to make and use the same.

This invention relates to improvements in carbureters.

The object of the invention is to provide a 15 simply constructed and easily operated and regulated carbureter which does not rely on heat to vaporize the gasolene, and which thoroughly mixes and prepares the mixture before it goes to the engine cylinder. By 20 thoroughly mixing the air and gasolene while cold and carrying it to the cylinder cold none of its expansion is lost by heat, and all the force of the mixture is obtained in the cylinder thereby developing much 25 greater power from the same number of cubic inches of mixture than if it were first heated.

Another object is to provide a carbureter so constructed as to render it almost impossible 30 to flood the cylinder, and which may be readily taken apart and assembled for cleaning and other purposes.

With these and other objects in view the invention comprises certain novel constructions, combinations and arrangements of parts, as will be hereinafter more fully described and claimed.

In the accompanying drawings—Figure 1 represents a side elevation partly in section. 40 Fig. 2 is a plan view of the float; Fig. 3 is a plan view of the throttle valve.

In the embodiment illustrated a cylindrical casing 1 is shown of any suitable or desired size and composed of any suitable 45 material preferably brass. This casing is preferably threaded at its upper and lower ends to receive the top 2 and bottom 3. The top 2 is preferably cone-shaped and screwed on the upper end of the casing 1, the apex 50 of said cone terminating in an upwardly extending pipe 4 provided with a throttle valve 5 which extends transversely across said pipe and is preferably constructed of a partition 6 having a circular opening 55 7 therein and provided at its oppo-

site sides with guides 8. A slide 9 is mounted to reciprocate in said guides at the will of the operator and is provided at its inner end with a semi-circular recess 10 to provide for a clear passage in the pipe 4 60 at all times, no matter how small. It is thus obvious that by drawing out the slide 9 the opening in the pipe is enlarged while pushing in the slide reduces the size of the opening. An apertured lug 11 extends laterally 65 from the slide 9 and is designed to be connected with an operating element such as a rod.

The casing 1 is provided at diametrically opposite points on its inner face with longitudinally extending grooves 12 and 13 in which are slidably mounted a removable fan frame 14. The upper cross bar 15 of this frame has a screw 16 threaded therethrough and held in adjusted position by a lock nut 70 17. The inner end of this screw 16 has a bearing 18 therein in the form of a socket in which the upper end of the fan shaft works as will be described. The lower cross bar 19 of the frame 14 has also a cone-bearing 20 80 therein.

Mounted to revolve in the bearings 18 and 20 is a fan-shaft 21 the opposite ends of which are pointed to form needle bearings to permit the shaft to revolve with the least 85 possible resistance.

A plurality of series of mixing blades 22 are mounted on the shaft 21 and each series of these blades is preferably fixed to a hub 23 which is screwed on the shaft 21, said 90 shaft being preferably screw threaded throughout its length. These mixing blades or fans are so connected with their hubs that they stand when applied at an angle to the shaft 21 with one side edge turned upwardly 95 and the other downwardly to provide for the turning of the shaft when a slight pressure of air is exerted on said blades.

The bottom 3 of the casing 1 has a feed chamber 25 depending therefrom and provided with an air inlet 26 controlled by an inwardly swinging gate 27 which is designed to be swung inward by the pressure of the air. An expansion spring 28 is attached at 100 one end to the gate 27 and at its other end to a screw-threaded spindle 29 which passes through an apertured ear 30 and is provided with a lock nut 31 which regulates the tension of the spring and the swinging of the gate which may be adapted to open easily or 110

not according to the adjustment of said nut 31. The lower end of the gate 27 has a recess 32 therein to permit a passage of air thereunder when closed. A pipe 33 connects the lower end of said feed chamber with a float chamber 34 and is provided with a valve 35 for controlling the supply of gasoline fed through said pipe 33 to the feed chamber 25. This float chamber 34 is preferably provided with a cap 36 screwed thereon and having a screw-threaded aperture 36' disposed centrally therein. An externally threaded pipe 37 is adjustably secured in said threaded aperture 36' and its inner end is designed to form a bearing for a float spindle or stem 38. This pipe 37 is connected with a gasoline supply tank, not shown, and is designed to admit gasoline to the float chamber 34, the admission being controlled by a valve to be described.

A float 39 composed of any suitable material, preferably cork coated with a solution of wood alcohol and shellac, is disposed in the chamber 34 and has a centrally disposed brass-lined bore 40 through which the spindle or valve stem 38 passes loosely and which forms a guide for the float. This stem 38 has its upper end pointed and ground very smooth and is fitted into the inner end 30 of pipe 37 forming a needle valve for controlling the quantity of gasoline admitted through said pipe. A stop 41 is carried by the stem above the float 39 and is designed to limit its upward movement, which when it 35 engages said stop on the rise of the gasoline in the chamber forces the valve into the pipe end and cuts off the admission of the gasoline. A stop 42 is also carried by the stem 38 below the float 39 and is spaced from said 40 float a slight distance and when the float falls on the lowering of the liquid level in the chamber 34 it will engage the stop 42 and force the stem down, thus opening the valve. When the float drops on the lowering 45 of the gasoline in the chamber the stem or spindle also drops sufficiently to open the valve and permit gasoline to flow into the chamber. By this means the gasoline is maintained at a certain level in the feed 50 chamber 25. The screwing of the pipe 37

into or out of the float chamber regulates the level of the gasoline in the feed chamber 25.

In the operation of this improved carbureter, when the engine is in motion or taking a charge, air is drawn into the casing 1 through the inlet 26, thereby forcing open the gate 27 and entering the feed chamber 25. The resistance offered by the gate causes the air to be deflected down against the bottom of the feed chamber 25, and thus draws with it in its passage to the casing 1, the gasoline from said feed chamber. As the air is drawn into the casing 1 it impinges against the fans or blades 22 which causes them to revolve rapidly, owing to their peculiar construction, and the mounting of the shaft 21 on needle bearings, and the air and gasoline is thus commingled and vaporized. This mixture passes through the throttle valve into the cylinder of the engine where it is exploded and furnishes power.

I claim as my invention—

The herein described carbureter comprising a flanged base of inverted cone shape having a centrally disposed inlet for the 75 gases to be mixed, a flanged cone shaped top having a throttle valve at its upper discharge end, a cylindrical casing having its upper and lower ends detachably engaged with the flanges of the top and base and 80 formed on its inner wall at diametrical opposite points with vertical grooves, a rectangular frame having its upright side bars 85 slidably engaged with said grooves and its upper and lower bars provided with cone 90 seats, one of the latter being adjustable, an upright threaded shaft having cone shaped ends to engage said cone bearings, a series of superimposed fans having their hubs threaded on said shaft and clamping nuts on said shaft above and below the hubs to adjustably secure the fans in position.

In testimony whereof I have hereunto set my hand in presence of two subscribing witnesses.

FRANK S. PIERCE.
